Patented June 29, 1920.

UNITED STATES PATENT OFFICE.

JOHN COOPER MILNES, OF CHICAGO, ILLINOIS.

SCREEN-MARKER.

1,345,211.

Specification of Letters Patent. Patented June 29, 1920.

Application filed September 8, 1919. Serial No. 322,276.

To all whom it may concern:

Be it known that I, JOHN COOPER MILNES, a citizen of the United States, residing at Chicago, in the county of Cook and State of

5 Illinois, have invented a new and useful Screen-Marker, of which the following is a specification.

This invention relates to marking devices adapted for use in connection with window 10 and door screens.

An object of this invention is to provide novel means for attaching a marking plate or card to the frame of the usual window and door screen structures, in order that the 15 proper location of the screens so marked may be readily determined by examining the identification card.

With the above and other objects in view, which will appear as the description proceeds, the invention resides in the combination and arrangement of parts and in the details of construction hereinafter described and claimed, it being understood that, precise embodiment of the invention shown can 25 be made without departing from the spirit of the invention.

The invention has been illustrated in its preferred embodiments in the accompanying drawings wherein:

30 Fig. 1 is a fragmental side elevation of a window or door screen, showing the invention applied to the top rail of the screen.

Fig. 2 is a top plan view of the device with the card holding plate in its open position.

Fig. 3 is a transverse sectional view taken on the line 3—3 of Fig. 1.

Fig. 4 is a longitudinal sectional view taken on the line 4—4 of Fig. 3.

40 Fig. 5 is a perspective view of the card holding plate.

Referring to the drawing there is shown the conventional door or window screen S and the usual top rail R of the screen frame.

45 The invention comprises an oblong card holding plate 10 of rectangular form and a housing or shielding plate 11. The card holding plate 10 has its intermediate portions offset as indicated at 12 to define a card receiving depression, and portions of the plate 10 adjacent the ends of the depression are upstruck to provide resilient gripping fingers or tabs 13 adapted to engage and secure a marking card 14 which is received within the depression of the plate 10. An extension or arm 15 is formed at

one end of the plate 10, and a longitudinally disposed manipulating finger 16 extends perpendicularly from one lateral edge of the arm 15.

60 Nails or other securing devices 17 extend through the shielding or housing plate 11 to securely attach this plate to the rail R, and one of the nails also extends through that end of the plate 10 which is remote from the arm 15, thereby pivotally securing this plate between the rail R and shielding plate 11. One end of the shielding plate 11 has a recess 18 formed in one of its longitudinal edges for the reception of the manipulating 70 finger 16 when the plate 10 has been moved to its closed or housed position.

In use, the marking or identification card 14 may be inscribed with any desired data and preferably with an inscription that 75 will readily determine the proper location of the screen in any portion of a selected building; and by way of illustration the present card 14 has been marked to indicate that this screen is to be used in right 80 hand window of front room or third floor of building 105 E street. This card 14 is then positioned under the fingers 13 within the depression of the plate 10 and the plate 10 is in turn moved about its pivot to its 85 housed or shielded position between the rail R and shielding plate 11. Now the screen may be positioned within its window or door frame without injury to its marking or identification card and this card may be 90 readily examined at any subsequent time by simply gripping the manipulating finger 16 and moving the plate 10 laterally to its open or exposed position.

Having thus described my invention 95 what is claimed is:—

A frame marker including a shielding plate positioned in spaced relation to the frame, a card-holding plate positioned between the shielding plate and the frame, 100 said card-holding plate being formed of sheet metal of uniform thickness and having an offset portion defining a card-receiving depression, an identification card positioned within the depression, resilient 105 gripping fingers struck from the card-holding plate and adapted to resiliently engage the identification card, a reduced extension formed at one terminal of the card-holding plate, a securing device extending through 110 apertures formed in the shielding plate and card-holding plate and projecting into the

frame, thereby forming a pivot for the card-holding plate and securing means for the shielding plate, a separate securing device extending through the shielding plate and 5 projecting into the frame, and adapted to engage the reduced extension to thereby limit the inward movement of the card-holding plate about its pivot.

In testimony that I claim the foregoing as my own, I have hereto affixed my signature in the presence of two witnesses.

JOHN COOPER MILNES.
